[57] CLAIM

The ornamental design for a pen assembly, as shown and described.

DESCRIPTION

FIG. 1 is a perspective view of the pen assembly comprising a pen and a pen holder showing my new design;

FIG. 2 is a side elevation view of the pen assembly;

FIG. 3 is a bottom plan view of the pen assembly;

FIG. 4 is a top plan view of the pen assembly of FIG. 2;

FIG. 5 is a side elevational view of a second embodiment of my new design of FIG. 1 in an exploded condition; and,

FIG. 6 is a side elevational view of FIG. 1 in an exploded condition.
